GAME TOY

Matilda A. Williamson and Matthew W. Svetlic,
Pittsburgh, Pa.

Application January 21, 1935, Serial No. 2,730

1 Claim. (Cl. 273—104)

This invention relates to a game toy, and important objects thereof are to provide a game toy of the character described, which is fascinating and instructive and entertaining for both children and adults, which is portable and may be played either indoors or outdoors, which may be compactly collapsed to facilitate its storage and transportation, which is readily understood but requires considerable skill to play successfully, which is simple in its construction and arrangement, durable and attractive, and comparatively inexpensive to manufacture.

With the foregoing and other objects in view which will appear as the description proceeds, the invention consists of the novel construction, combination and arrangement of parts herein specifically described and illustrated in the accompanying drawing, but it is to be understood that changes in the form, proportions and details of construction may be resorted to that come within the scope of the claim hereunto appended.

In the drawing wherein like numerals of reference designate corresponding parts throughout the several views:

Figure 1 is a top plan view of a game toy constructed in accordance with the invention.

Figure 2 is an enlarged top plan view of a supporting bar.

Figure 3 is a full-size side view of a pin, partly in cross section, and illustrating its connection with the supporting bars. Figure 4 is a similar view of the connecting element.

Figures 5 and 6 are top plan views of different types of quoits employed in the operation of the present invention.

Referring in detail to the drawing, the present invention comprises a plurality of flat supporting bars 1, which may be constructed from wood, metal, fibre, or any other suitable material. Each 40 of the supporting bars has rounded ends and provided with a pair of apertures 2 disposed adjacent to respective ends thereof.

The supporting bars 1 are of uniform lengths and otherwise identical in construction. The 45 supporting bars are all joined together by having their respective adjacent ends united by toggle-joint connections. A screw bolt 3 extends vertically through the apertures 2 of adjacent ends of the supporting bars, and provided with a bottom 50 washer 4 and a top washer 5. The bottom washers are disposed below the supporting bar ends and provide seats for the latter. The top washers are disposed above the supporting bar ends and tightly engaged on the screw bolts to provide 55 properly maintained and frictionally retarded op-

erations of the toggle-joint connections of the supporting bars.

The supporting bars 1 support a peg or pin 6 at each connected end thereof. The bottom of each of the pins is provided with a pocket 7 in which a threaded bushing 8 is permanently secured to provide a detachable connection with respective screw bolts 3.

The pins 6 seat upon the top washers 5 and are rigidly supported in the vertical positions. The 10 pins may be readily detached from their positions for the purposes of storage or transportation of the device, and their removal or replacement will in no way affect the connections of the supporting bars relatively to each other. The 15 pins may have any desired configuration and constructed from any suitable material.

The surface of the pins 6 are preferably fancifully colored. As illustrated in Figure 3, the top portion of the pin is red, the intermediate portion is white, and the bottom portion is blue. It is, of course, obvious that the surface of the pins may be of colors varying from each other and each pin colored differently, or that each pin be of a single color.

The top of each pin 6 is provided with indicia 9 in the form of a numerical figure. The embodiment of the device, shown in Figure 1, employs the numerical figures from zero to nine, with each of the pins having a different numerical figure. It is apparent, however, that the numerical designations may be widely varied, from the disclosure illustrated, to best meet any condition found in practice.

In playing the game toy, quoits, in the form of a horseshoe 10 or rings 11 are employed. The connected supporting bars 1, with the fixed pins 6, is positioned on the floor, ground, stand, wall, or any other suitable place. The players, positioned at a distance from the device, toss the quoits in 40 the endeavor to ring the pins. The players will naturally try to ring the pin bearing the highest numerical designation, as the total of the latter on pins rung with the player determines his status as winner or loser.

It will here be noted that, by constructing the supporting bars 1 of uniform lengths and by uniting same by toggle-joint connections, in the manner stated, the device may be extended or contracted to widely vary the relative position of the 50 pins 6 with respect to each other, whereby the game may be rendered more or less difficult to suit the pleasure of the players.

The present invention provides an inexpensive and durable game toy, which is exceptionally 55

enjoyable for both children and adults by admitting the exercise of competitive skill in an entertainment readily understood and fascinating in its execution.

5   What we claim is:

In a game toy, the combination of a plurality of pins, each of said pins having identifying indicia and being provided with a pocket in the lower end thereof, an internally threaded bushing secured in each of said pockets, a plurality of supporting bars, the end portions of each adjacent pair of supporting bars overlapping each other and being provided with apertures, screw

bolts extending through the apertures in respective overlapping end portions for pivotally connecting the latter together, said screw bolts being threadedly engaged in respective bushings for securing said pins in the vertical position on said supporting bars, bottom washers mounted on said screw bolts to provide seats for said overlapping end portions, and top washers threadedly engaged on said screw bolts between said bushings and said overlapping end portions for adjusting the pivotal connection of the latter. 5

MATILDA A. WILLIAMSON.
